FOOT TYPE HIGH LIFT JACK

Ion V. K. Hott and David M. Goldzwig, Dayton, Ohio, assignors to The Joyce-Cridland Company, Dayton, Ohio, a corporation of Ohio

Application December 26, 1952, Serial No. 328,032

7 Claims. (Cl. 254—7)

This invention relates to a foot type high lift jack and more particularly to a foot type high lift jack that is portable and adapted for heavy duty, as for example, for use in lifting diesel engines, although not necessarily so limited.

In roundhouses and in railroad yards it is at times necessary to lift or raise heavy loads. The equipment required to raise these heavy loads must, of necessity, have sufficient strength to carry the load and be portable, so that the equipment may be moved into operative position with a minimum amount of labor and, at the same time, be so balanced that in moving the equipment from place to place the chances of the equipment tipping or falling over are reduced to a minimum. It is important for the sake of safety, in that equipment that weighs thousands of pounds and extends upwardly eight feet or more from the floor, creates a hazard if it is not well balanced. In order to facilitate the ease of handling, light weight of the equipment is an important factor.

An object of this invention is to provide a foot type high lift jack that is made from light weight material, and at the same time provided with sufficient strength that it is capable of raising heavy loads through a considerable distance without danger of upsetting. This has been accomplished by making many of the parts from light weight metal, such as aluminum alloy, the parts being so designed and the structure so balanced and reinforced that stresses in the frame structure are held to a minimum. A comparatively large flat base is used, adapted to be seated directly on the concrete or the floor or on the ground. Another object of this invention is to provide wheels for transferring the jack from one place to another, the wheels being mounted upon movable frames or supports that may be mechanically driven from inoperative position into operative position, or vice versa.

Another object of this invention is to provide a frame assembly to properly guide the lifting foot, which frame assembly is made from parts produced from light weight material, which parts are available on the open market, the parts being reinforced so as to provide adequate strength. This has been accomplished by using aluminum-alloy I-beams as vertical frames, braced by light weight strips of aluminum alloy metal having the desired tensile strength, and angularly disposed, so as to support the frame structure in a vertical position when in use, the flanges of the I-beams being lined with semi-cylindrical rail members functioning as guides and supports for rollers used in guiding the foot in a vertical path.

Another object of this invention is to provide a pneumatic drive used in actuating the jack screw, having mounted thereon a lifting foot, the same jack screw being used in lifting the jack from the base of the frame structure upon wheels forming a carriage used in moving the jack from one position to another, the lifting mechanism having two operative ranges of positions, one, when the lifting foot is to be used in raising the body from one range of levels. The other position is used in raising a body from a lower range of levels.

2

Other objects and advantages reside in the construction of parts, the combination thereof and the mode of operation, as will become more apparent from the following description.

5 In the drawings,

Figure 1 is a perspective view of the foot type high lift jack.

Figure 2 discloses a support adapted to be used in association with the foot of the high lift jack shown in Figure 1.

Figure 3 is a vertical cross sectional view of the high lift foot jack.

Figure 4 is a fragmentary, enlarged, detail, cross sectional view of the jack screw and parts associated therewith.

Figure 5 is a cross sectional view taken substantially on the line 5—5 of Figure 3.

Figure 6 is a fragmentary, front elevational view of the base with parts broken away.

Figure 7 is a fragmentary side elevational view of the mechanism used in raising the high lift upon wheels with the foot at high level, with parts broken away and other parts shown in section.

Figure 8 discloses a plurality of high lift jacks used in lifting a locomotive or a Diesel engine, as the case may be.

Referring to the drawings, the reference numeral 20 indicates a base plate forming a bed for a high lift jack. On the under side of the base plate 20 are positioned a plurality of foot pads 22 upon which the base plate rests when the jack is in actual use. A pair of vertically extending parallel I-beams or standards 24 are fixedly attached to the base plate and supported thereon. In order to prevent tilting of the I-beams with respect to the base 20, a pair of brackets 26, which may be referred to as heel brackets, are secured to the rear flanges of the I-beams 24 and rigidly bolted to the base plate 20. In addition to the heel brackets 26, a pair of toe brackets 28 are mounted on the front side of the I-beams and bolted thereto and also bolted to the base plate 20. These I-beams are preferably made from a light weight material, such as aluminum or an aluminum alloy, or some other suitable light weight material.

A capping member 30 is fixedly attached to the I-beams 24 supporting the upper ends of the I-beams in fixed spaced relation. The I-beams 24 are braced by a pair of braces 32 attached to the opposite sides of the capping member by screws or bolts 33, the braces 32 extending downwardly to a bracket 34 attached in space relation from the bottom of the I-beams 24. The braces 32 have their lower ends 32a extending inwardly and are attached to the base 20 by suitable bolts 36.

A gear casing 40, positioned between the I-beams 24 and fixedly attached to the base plate 20, has journalled therein a jack screw 42. The lower end of the jack screw 42 has keyed thereto a bevelled gear 44 resting upon a race 46 of an end thrust ball bearing having a stationary race 48 resting upon a support 21 threadedly engaging the gear casing 40. As clearly seen in Figure 3, there is a gap 23 between the leading edge of the support 21 and the base plate 20. This gap extends rearwardly to approximately the center of the axis of rotation of the jack screw 42, so that when a load is thrown upon the jack screw 42, as will be explained more fully later, the gear casing is permitted to rock upon the base 20, so as to eliminate any binding action between the jack screw and the gear casing. Suitable anti-friction bearings 50 are mounted in the annular bearing seat in races 46 and 48. The upper end of the jack screw 42 terminates in a cylindrical portion 59 journalled in a bearing seated in a suitable cavity in the capping member 30. The diameter of the cylindrical portion 59 is substantially equal to the diameter of member 42 measured at the root of

the threads. A cup-shaped collar member 61 is slidingly mounted on the cylindrical portion 59 and normally rests on top of the threads of the jack screw 42.

The gear casing 40 supports a driving unit including a bevelled pinion 60 driven through suitable speed reducing gears 62 driven from an air motor represented broadly by the reference numeral 64. The controls and the source of energy for the air motor will be described more fully later.

As may best be seen by referring to Figures 3 and 4, the jack screw 42 is used in actuating a nut 70 non-rotatably mounted in a vertically disposed carriage 72 provided with a vertically disposed aperture, through which the jack screw 42 extends. The carriage 72 is provided with a foot portion 74 that projects forwardly between the I-beams 24. The carriage is guided in a vertical path by suitable grooved wheels 80 and 82, the grooved wheels 80 being arranged on opposite sides of the carriage near the top thereof and the grooved wheels 82 being arranged on opposite sides of the carriage near the bottom thereof. These grooved wheels 80 and 82 ride on substantially semi-circular rails 86 and 88, the rails 86 being secured to the rear inner flanges of the I-beams 24, the rails 88 being secured to the opposite flanges of the I-beams 24.

As a load is applied upon the foot portion 74, it can readily be seen from an inspection of Figure 3 that the carriage will tend to rotate in a counterclockwise direction, so that the upper wheels 80 will exert a pressure against the rails 88 and the lower wheels 82 will exert a pressure against the rails 86. The wheels 80 and 82, being provided with semi-cylindrical shaped annular grooves, will always track on the rails 86 and 88, even though the flanges will flex slightly. It is quite obvious that the load upon the foot portion 74 will cause the carriage 72 to tend to spread the inner flanges of the I-beams 24. Being these I-beams are made from such material as aluminum alloy, there will be a tendency for the webs of the I-beams to flex or bend, so that the inner I-beam flanges will tend to move outwardly and the outer I-beam flanges will tend to move toward each other. Each of the I-beams has been provided with a vertically disposed plate 90, as best seen in Figure 5, snugly seated between the outer flanges of the I-beams. The plates 90 cooperate with the webs 92 to prevent buckling of the webs and thereby deter flexing of the flanges. By utilizing semi-circular or semi-cylindrical rails and grooved wheels, the wheels will properly track on the rails, even though there may be a slight flexing when the foot portion 74 supports an extremely heavy load.

A bearing collar 94, as best seen in Figure 4, is positioned between the nut 70 and a shoulder 96 projecting inwardly from the aperture in the carriage 72. This bearing collar 94 relieves any binding action that might tend to occur if the nut 70 were integral with the carriage by allowing the nut to shift in the carriage. By rotating the jack screw, it can readily be seen that the carriage 72 and the foot portion 74 may be raised and lowered. When raised upwardly, the carriage may engage the collar 61, causing this collar to be slid upwardly on the reduced portion 59.

A three-way (up, off and down) valve member 100 is manually controlled by a lever 102 for opening and closing the valve. By opening the valve, air may be admitted to the air motor from a hose 106 connected to a suitable air supply. As the valve 100 is opened, air is admitted to the air motor, which drives the jack screw in one direction or the other, depending upon which way the three-way valve 100 is opened, as is well known to those skilled in the art.

The safety device includes an air shut-off arm 110 connected to the valve 100 and projecting between the two I-beams where the arm is secured to a vertically disposed shaft 112 journalled in brackets 114 and 116, supported upon the I-beams upon suitable cross mem-

bers 118 and 120 respectively. The shaft 112 supports at its lower end a cam 130 and at its upper end another cam 132, the cams 130 and 132 being mounted in the path of a pin 134 projecting from the carriage 72. By this arrangement, if the carriage 72 is lowered to a vulnerable position, the pin 134 will engage the cam surface 130 to rotate the shaft 112, thereby actuating the arm 110 to close the valve supplying air to the air motor. Likewise, if the carriage is raised upwardly to such an extent that the pin 134 comes in contact with the cam 132, the shaft 112 is again rotated, so as to cause the arm 110 to close the valve.

A plurality of these high lift jacks may be used in lifting heavy vehicles, such as diesel engines, locomotives, et cetera, as clearly illustrated in Figure 8. That being the case, it is necessary to provide dollies or trucks to permit wheeling the jacks in position. This has been accomplished by mounting an axle or shaft 131 journalled in suitable bearings in brackets 28. The brackets 28 may be provided with tubular extensions 28a for supporting the shaft or axle. The outer ends of the shaft 131 have keyed thereto brackets 133 having fixedly secured thereto spindles 135, rotatably supporting the wheels 136, there being one wheel on either side of the jack. A control bracket 140 is keyed to the axle or shaft 131 and is mounted between the brackets 28, so that as the bracket 140 is rotated, the axle or shaft 131 is rotated, and thereby the brackets 133 are rotated so as to raise or lower the wheels 136 with respect to the jack.

Due to the fact that these jacks are extremely heavy, a power mechanism is used in actuating the bracket 140 in a clockwise or counterclockwise direction, as viewed in Figure 7. The bracket 140 has pivotally attached thereto a pair of link-like members 142 interconnected by a transverse member 144 adapted to engage the lower end of a bracket 146 pivotally attached to the upper ends of link members 142. The bracket 146 is normally biased into the extended position by a torsion spring 148. The upper end of the bracket 146 is provided with a slot adapted to receive the downwardly projecting lip or flange 150 projecting downwardly from the carriage 72. Thus, by rotating the jack screw 42 by the air motor, so as to lower the carriage 72, to cause the lip 150 to engage the bracket 146, it can readily be seen that the brackets 133 will be rotated in a clockwise direction, as viewed in Figure 7, so as to cause the wheels 136 to engage the floor, or base, upon which the jack stands, to raise the forward end of the jack up from the floor. The rear end of the jack is provided with a rearwardly projecting member 170

50 provided with a cam surface 172 on either side thereof, adapted to engage a cam 174 mounted on a handle 176 pivotally mounted at 178 to a fork 180 supporting a wheel 182. The fork 180 terminates in a stubshaft positioned in an aperture in member 170. In member 170 there is 55 a spring, not shown, that biases the fork 180 and the wheel 182 upwardly, so that the wheel 182 is suspended in spaced relation from the floor when the handle is in the up and dotted position, as shown in Figure 7. As the handle 176 is rotated from the dot-dash position 60 shown in Figure 7 into the full line position shown in Figure 7, the cam 174 engaging the cam follower 172 raises the rear end of the jack up from the floor. By this arrangement, it is possible for the operator to tow the jack from one position to another by manipulating the handle 176. This handle is also used in steering the wheel 182, so as to control the direction of movement of the jack.

When the jack is actuated into position, as shown in Figure 8, there being one jack for each corner of the diesel engine, the handle 176 is raised from the full line position shown in Figure 7 to the dot-dash position shown in this figure, so as to lower the rear end of the jack. The motor is connected by a suitable hose 106 to the air supply. The jack screw is rotated in the opposite direction from which the brackets 133 were rotated in raising

the jack from the floor, so as to cause the forward end of the jack to rest upon the foot pads 22. The bracket 142 may then be folded into the position shown in Figure 3.

In the event it is necessary to lower the foot portion 74 to a position lower than the releasing position of the wheels shown in Figure 7, the carriage 72 may be lowered with the outer link members 142 in the position shown in Figure 3 until the lip 150 engages the links 140. Then, by lowering the carriage 72, the lip 150 engaging the links 140 raises or lowers the wheels, as the case may be, with the foot portion in a lower position, in which event it is adapted to be projected under a load to be lifted only slightly higher than the top of the foot portion 74.

All of the jacks that are to be used for raising a locomotive are moved into position prior to the raising of the locomotive. After the jacks have been moved into position, a hose from each of the motors of the jacks are connected to a common source of supply of air under pressure. The relative movement of the several motors and the several jack screws 42 raising the several foot portions 74 is controlled by a plurality of valves 190, one for each jack. The operator tending the valves 190 observes the position of the several foot portions 74 by observing the graduated scale 200 found on each jack and the indicant 202 traveling with the carriage 72. If one jack travels faster than the others, the corresponding valve 190 is partially closed, so as to reduce the air supply to that particular jack. Thus, it is possible to raise all four corners of a locomotive uniformly.

In some cases the normal position of the foot portion 74 may be too low to raise the body to the proper height. A foot extender 212 may be slipped over the end of the foot portion 74, so that the top of member 210 engages the under side of the load. A foot extender, having the proper height for a particular job, may be used.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described our invention, we claim:

1. A high lift jack assembly including a base, a vertically disposed jack screw supported upon the base, frame means extending upwardly from the base for supporting the upper end of the jack screw, a carriage mounted upon the jack screw and guided by the frame means, said carriage having a downwardly projecting abutment portion, and a wheel assembly for transporting the high lift jack from one position to another, said wheel assembly including a horizontally disposed shaft, means for pivotally mounting the shaft in spaced relation from the base and near one end thereof, a pair of brackets, one on each end of the shaft and fixedly keyed to the shaft, a pair of pintles, one for each of the brackets and fixedly attached thereto, wheels mounted on the pintles, bracket means attached to the shaft and aligned with the downwardly projecting abutment portion of the carriage so that as the carriage is lowered the abutment portion engages the bracket means to rotate the shaft to thereby lower the wheels with respect to the base of the high lift jack to raise one end of the base upwardly, a third wheel means for supporting the other end of the base, and manually controlled means for lowering the relative elevation of said third wheel means with respect to said base to thereby raise said other end of the base so that when the first mentioned wheels and the third wheel means are lowered the high lift jack may be transported on the wheels.

2. A high lift jack assembly according to claim 1, wherein the third wheel means includes a bifurcated fork

for supporting the third wheel, a lever pivotally attached to the bifurcated fork, and cam means actuated in response to movement of the lever for raising and lowering the third wheel with respect to the base of the jack.

5 3. A device according to claim 1, wherein the third wheel means includes a bracket having a vertically disposed recess, means for supporting the bracket near one end of the base with the recess being located in a portion projecting beyond the end of the base, a substantially vertically disposed shaft pivotally mounted in the recess, a bifurcated yoke projecting downwardly from the lower end of the shaft for supporting the third wheel, a lever pivotally mounted to the yoke, and eccentric cam means mounted on the lever so that as the lever is rotated about its pivot, the cam means engages the bracket to raise and lower the third wheel with respect to the base.

10 4. A high lift jack assembly according to claim 1, wherein the bracket means attached to the shaft and aligned with the abutment portion of the carriage includes a main bracket portion and a link extension pivotally mounted to the main bracket portion, the link extension when vertically disposed projecting upwardly to engage the abutment portion at a higher level than when the link extension is folded so as to extend parallel to the 15 main bracket portion.

20 5. A high lift jack assembly according to claim 1, wherein the bracket means includes pivotally mounted extension means having two positions, one a vertical position and the other a horizontal position, the abutment portion engaging the extension means when in the vertical position and engaging the main body of the bracket means when the extension means is in a horizontal position.

25 6. The combination of a high lift jack with a truck assembly for transporting the high lift jack, said high lift jack including a frame assembly having a base, a vertically disposed jack screw rotatably mounted upon the base, a vertically disposed frame for supporting the upper end of the jack screw, said vertically disposed frame projecting upwardly from the base, a carriage mounted upon the jack screw, said carriage having a foot portion, said truck assembly including a pair of front wheels and a rear wheel, means responsive to the downward movement of the carriage for lowering at least some of the 30 wheels with respect to the base so as to shift the support of the jack screw from the base to the wheels, said means including a safety mechanism adapted to buckle in the event the wheels are lowered beyond predetermined limits.

35 7. The combination of a high lift jack with a truck assembly for transporting the high lift jack, said high lift jack including a base normally supporting the high lift jack, a vertically disposed jack screw mounted upon the base, means for supporting the upper end of the jack screw, a carriage mounted for vertical movement by the jack screw, said truck assembly including a pair of front wheels, means for lowering the front wheels in response to vertical movement of the carriage, said last mentioned means including a safety device for disengaging the carriage from said means when the front wheels are lowered beyond a predetermined position.
